DANIEL McFARLAN MOORE, OF NEWARK, NEW JERSEY, ASSIGNOR TO
MOORE ELECTRICAL CO., OF NEW YORK, N. Y., A CORPORATION OF
NEW YORK.

AUTOMATIC GAS-FEED FOR VACUUM-TUBES.

No. 856,484.

Specification of Letters Patent.

Patented June 11, 1907.

Application filed May 8, 1906. Serial No. 315,730.

To all whom it may concern:

Be it known that I, DANIEL McFARLAN MOORE, a citizen of the United States, and a resident of Newark, in the county of Essex and State of New Jersey, (with post-office address 52 Lawrence street,) have invented certain new and useful Improvements in Automatic Gas-Feeds for Vacuum-Tubes, of which the following is a specification.

10 My present invention relates to that class of devices termed vacuum tubes and which are supplied with electrodes or terminals for causing electric energy to pass through the contained gas or vapor.

15 The invention is particularly useful for vacuum tube or vapor electric lamps, but may also be applied to vacuum or vapor rectifiers, X-ray tubes, wireless telegraph apparatus or other devices which employ a vacuum 20 through which the electric energy passes.

The object of my invention is to prevent changes in the degree of vacuum due to the passage of the electric energy and consists in an improved means for automatically supplying the gas or vapor to the vacuous spaces so as to maintain the desired gas or vapor tension.

25 The invention consists essentially in the combination of a vacuum tube, a thermostat heated by current varying in amount with the resistance of the gas in the tube, and means controlled by said thermostat for supplying gas to the tube in regulated amounts so as to maintain the gas tension or density 30 therein at substantially normal degree.

35 The invention consists further in the combination with a vacuum tube, of an electrically heated thermostat connected to the circuit of the tube, and means controlled in their 40 action by said thermostat for supplying gas to the tube.

The invention consists also in the special 45 novel combinations of devices hereinafter described and claimed, and comprising among others the combination of a vacuum tube, a valve for admitting gas to the tube, and a thermostat controlling the action of said valve and heated by a current taken from the current supply for said tube and 50 varying in amount with the resistance of the gas within the tube.

In the accompanying drawings, Figure 1 is a general side elevation and partial verti-

cal section of an apparatus embodying my invention. Figs. 2 and 3 illustrate modifications. Fig. 4 is a modification of the circuits.

For the purposes of illustration only, I will describe the invention as applied to a vacuum tube lamp in which the gas tension or density is to be maintained at such a degree that a decrease of the density will have the effect of lowering the resistance of the gas to the passage of an electric current.

1 indicates the vacuum tube and 2 the usual internal electrodes, by means of which electrical energy of any desired form or character may be made to pass through the contained gas or vapor.

3 is a tube or pipe through which gas may be fed into the tube to bring the tension thereof back to normal when it shall have decreased owing to the action of the electrical current flowing in the tube. If the gas is supplied to the tube through the operation of a valve or similar gas feed controlling the flow from a body of gas of a tension greater than that in the tube, I prefer to employ the form of valve described in my prior application for patent filed Aug. 21st, 1905 and in a division thereof filed April 16th, 1906, but might employ any other construction of valve sufficiently delicate and certain in its action.

4 indicates a valve chamber containing a gas of a density or tension greater than that in tube 1 and supplied with gas from any source. Such source may be the atmosphere fed through a chemical for removing its oxygen as described and claimed in my application for patent filed April 2nd, 1906, S. N. 309,286 or may be a gas generator as described and claimed in my application for patent filed April 16th, 1906, S. N. 311,815 or a tank charged with the desired gas as described and claimed in my application for patent filed April 2nd, 1906, S. N. 309,283 or may be any other source.

Interposed in the passage between the chamber 4 and pipe 3 is a mass of porous material 5 forming a plug for the tube 3 and surrounded by a sealing body of liquid 6 such as mercury which should be normally maintained at such height as to leave none or but little of the tapered tip of the plug exposed above the level of the liquid. Plug 5 is of a

porous material like porous electric light carbon and is adapted, when exposed to the gas in chamber 4, to allow gas to percolate or flow through its pores in minute amount to 5 the feed tube or pipe 3. Any means may be used for adjusting the level of the mercury, as for instance, an adjustable plunger or liquid displacer 7. Variations in the height 10 of the liquid 6 are brought about through the action of a thermostat heated by current flowing in a circuit formed in part of the gas within the tube 1. Any form of thermostat may be employed. In Fig. 1 a mercury 15 thermostat is shown, and the liquid 6, which is mercury, may be a part of the mercury of said thermostat so that its level will rise and fall with the expansion and contraction of the body of mercury due to changes in its heat.

20 9 indicates the chamber for the mercury thermostat and 10 a heating coil surrounding the same. The bulk of the mercury in chamber 9 as compared with that in the connected tube or chamber in which mercury 6 is located is preferably large so that the effects of 25 contraction or expansion, due to change of heating effect of coil 10, will be multiplied at the valve. Heating coil 10 is connected, in Fig. 1, in shunt to the main circuit through 30 the tube. Normally, and when the gas tension and hence resistance of the circuit through the tube are normal, sufficient current will be forced to flow through the heating coil of the thermostat to maintain the level of the liquid 35 6 at a point where no or but little gas can leak into the feed tube 3. If, however, the resistance of the gas in tube 1 decreases, owing to decreases of the gas tension, less current will flow in the heating coil of the thermostat 40 and the thermostat will contract so that the valve will be opened or more fully opened by a change in the level of its liquid and thus allow gas to flow to the tube 1 until the gas tension or density in said tube is restored to 45 normal. More current will then flow through the coils of the thermostat and the flow of gas to the tube will be shut down or cut off.

Fig. 2 shows a modification wherein the 50 thermostat is in the direct circuit with electrodes 2 of the tube and operates to change the level of liquid in the valve by operating on a liquid displacer or plunger 7. In this figure, 12 indicates an expandible rod of any suitable material included in the circuit of the 55 electrodes 2 and heated by the current flowing through the same. The rod 12 is sustained from a support 13 and its action may be assisted by a spring 14. The plunger 7 is connected to the lower or free end of rod 12 60 by a lever 15. When the gas tension or density in the tube 1 decreases, more current flows in the rod 12 and by heating the same causes it to expand thus raising plunger 7 and allowing the level of the liquid 6 to fall 65 so as to feed more gas to the tube 1. The

restoration of the density or tension of the gas in tube 1 brings about a decreased flow of current in the rod 12, which thereupon contracts and shuts or partially shuts the valve.

Obviously, the thermostat might be connected in other ways to the circuit. Thus for instance, as shown in Fig. 4, it might be in the primary of a potential raising converter whose secondary supplies the tube. The mains to which the converter is connected being constant potential mains, the thermostat would act in the manner described in connection with Fig. 2 and would vary in its effect with the variation in the electrical resistance of the gas within the tube 75 due to change of gas tension or density.

In the modification shown in Fig. 3, the thermostat controls the action of a valve not by direct mechanical connection, but through an electrical device comprising an electromagnet, the coils of which are indicated at 16. The movable core of said magnet is connected to the plunger or displacer 7 and the circuit of said magnet is closed and opened by changes in the condition of the thermostat. In the case of a mercury thermostat, the circuit may be closed and opened through changes of height of the column of mercury of the thermostat, said column forming a part of the circuit of the coil 16 and any suitable source of electric energy 17.

The operation of the device which will be readily understood from the previous description is briefly: When the gas tension in tube 1 decreases, more current flows through the coils of the thermostat, its mercury column rises and closes the circuit of the coils 16 and the core of the latter operates upon the valve so as to open or more fully open the same and feed gas to the tube to restore the gas tension or density therein.

What I claim as my invention is:

1. The combination of a vacuum tube, a thermostat heated by current varying in amount with the resistance of the gas in the tube, and means controlled by said thermostat for supplying gas to the tube in regulated amounts so as to maintain the gas tension or density therein at substantially normal degree.

2. The combination with a vacuum tube, of an electrically heated thermostat connected to the circuit of the tube, and means controlled in their action by said thermostat for supplying gas to the tube.

3. The combination of a vacuum tube, a valve for admitting gas to the tube, and a thermostat controlling the action of said valve and heated by a current taken from the current supply for said tube and varying in amount with the resistance of the gas within the tube.

4. The combination of a vacuum tube, a valve having a liquid by whose changes of height the flow of gas to the tube is con-

trolled, and a thermostat controlling the action of a valve and heated by a current varying in amount with the resistance of the gas in the tube.

5. The combination of a vacuum tube, a mercury thermostat heated by current varying in amount with the resistance of the gas and a gas passage opened and closed by variations in the level of the mercury of the thermostat and controlling in turn the passage of a gas to the tube.

6. The combination of a vacuum tube lamp, a valve consisting substantially of a

mass of porous material and a sealing liquid, a thermostat responsive to variations in the resistance of the gas in the tube, and means controlled by said thermostat for varying the height of the liquid and thereby controlling the flow of gas to the tube.

Signed at New York in the county of New 20 York and State of New York this 5th day of May A. D. 1906.

DANIEL McFARLAN MOORE.
